UNITED STATES PATENT OFFICE.

MARC ANTOINE PATTAY AND EUGÈNE JAQUEMOT, OF GENEVA, SWITZERLAND, AS
SIGNORS TO MAGNÉTAS LUCIFER, SOCIÉTÉ ANONYME, OF CAROUGE-GENEVA,
SWITZERLAND, A CORPORATION OF SWITZERLAND.

INDUCTOR FOR MAGNETO-ELECTRIC MACHINES.

Application filed January 21, 1928, Serial No. 248,326, and in Switzerland January 26, 1927.

The object of this invention is an improvement in inductors for magneto-electric machines, for instance in inductors for small machines serving for lighting of bicycles or for 5 the supply of electric current for pocket lamps.

They comprise the same as known inductors of magneto-electric machines, at least one pair of magnets which are applied against 10 the surface of an envelope of non-magnetic material by means of members which are wedged between the ends of the magnets and upon which fixing members are operating which are bearing against the envelope.

15 They differ, however, in this that the wedging members are made from magnetic material and do constitute one piece with the pole pieces which are in relation with the magnets exclusively by the intermediary of said wedging members, for the purpose of allowing the 20 magnets to become wholly utilized from the magnet point of view.

The drawing shows by way of example one 25 working form of the inductor according to invention.

Fig. 1 is a cross section according to line I—I of Fig. 2.

Fig. 2 is a section through the axis.

This working form comprises a cylindrical 30 envelope *a*—*b* made from non-magnetic material, for instance of brass, and consisting of a cylindrical portion *a* as well as of a bottom portion *b* having an outward projection *c*. Two permanent magnets *d*, *e* are applied 35 against the inner surface of the portion *a*. Said magnets, for instance of steel or cobalt, have a rectangular cross section and seen from the side (Fig. 1) show the form of half-circles which are separated one from the other by 40 short intervals or gaps *g*. The magnet faces, which border and limit each gap, are planes which are parallel to the axis of the inductor and are sloping more and more from the bisector plane of the gap the more the axis of 45 the inductor is approached. The gaps *g* are receiving pieces *h*—*i* which in side elevation have the shape of a trapezoid and which belong to members *h*, *j*, *i*, *k* which also comprise the pole shoes *j*, *k*. These latter are arranged 50 in such a manner that they nowhere are directly contacting with the magnets. The two members are made from magnetic material,

for instance from soft steel. Screws *l*, *m* are provided for displacing said members from the inside towards the outside, the bodies of the screws are traversing the members whilst their heads bear against the envelope *a*—*b*.

The inductor represented rotates around a fixed armature not shown in the drawing.

The working form described offers different advantages: thanks to the fact that the magnets are of semi-circular shape, their magnetic conditions are good ones because they approach the ratio which is esteemed the possibly best determined ratio between the length of the magnets and their cross section. Since the pole pieces are in no relation with the magnets except by the portions *h*, *i* of the members *h*, *i*, *j*, *k*, these magnets are evidently utilized up to their very ends, contrary to the case in which the pole shoes *j*, *k* were in direct relation with the magnets and therefore a perceptible economy is realized of the magnet material, the costs of which in the case of particular steels are sometimes very high.

The magnets may be more than two in number.

Instead of a rotary inductor a fixed one might be conceived and it might be utilized for machines of other kinds than those mentioned in the introduction of this description.

What we claim is:

Inductor for magnet-electric machines comprising in combination a plurality of 85 magnets, an envelope of non-magnetic material and wedging members of magnetic material, these wedging members being lodged between the adjacent ends of the magnets and adapted to apply these latter against the surface of said envelope of non-magnetic material, pole pieces constituting one piece with 90 said wedging members and which are in relation with the magnets solely by the intermediary of the wedging members, so as to allow 95 to wholly utilize the magnets from the magnet point of view, and fixing members which are operative on the wedging members and which are adapted to bear against said envelope of non-magnetic material.

In testimony whereof we have signed our names to this specification.

MARC ANTOINE PATTAY.
EUGÈNE JAQUEMOT.

CERTIFICATE OF CORRECTION.

Patent No. 1,686,343.

Granted October 2, 1928, to

MARC ANTOINE PATTAY ET AL.

It is hereby certified that the name of the assignee in the above numbered patent was erroneously written and printed as "Magnetas Lucifer Societe, Anonyme", whereas said name should have been written and printed as "Magnetas Lucifer Societe Anonyme", as shown by the records of assignments in this office; and that the said Letters Patent should be read with this correction therein that the same may conform to the record of the case in the Patent Office.

Signed and sealed this 8th day of January, A. D. 1929.

(Seal)

M. J. Moore,
Acting Commissioner of Patents.
